US00D338879S

United States Patent [19]
Iino

[11] **Patent Number:** **Des. 338,879**[45] **Date of Patent:** ** Aug. 31, 1993[54] **ELECTRONIC COMPUTER**[75] **Inventor:** **Masaaki Iino**, Yokohama, Japan[73] **Assignee:** **Kabushiki Kaisha Toshiba**,
Kanagawa, Japan[**] **Term:** **14 Years**[21] **Appl. No.:** **938,671**[22] **Filed:** **Sep. 1, 1992****Related U.S. Application Data**

[63] Continuation of Ser. No. 461,463, Jan. 5, 1990, abandoned.

[30] **Foreign Application Priority Data**

Jul. 6, 1989 [JP] Japan 1-24754

Primary Examiner—Wallace R. Burke**Assistant Examiner**—Freda S. Nunn**Attorney, Agent, or Firm**—Banner, Birch, McKie & Beckett[57] **CLAIM**

The ornamental design for an electronic computer, as shown and described.

DESCRIPTION

FIG. 1 is a top, front and right side perspective view of an electronic computer showing my new design;
 FIG. 2 is a top plan view thereof;
 FIG. 3 is a bottom plan view thereof;
 FIG. 4 is a front elevational view thereof;
 FIG. 5 is a rear elevational view thereof;
 FIG. 6 is a left side elevational view thereof;
 FIG. 7 is a right side elevational view thereof;
 FIG. 8 is a right side elevational view thereof, the display panel in the closed position;
 FIG. 9 is a front elevational view thereof, the display panel in the turned position;
 FIG. 10 is a front elevational view thereof, the display panel in the closed position; and,
 FIG. 11 is a top plan view thereof, the display panel in the closed position.
